CLAIM

The ornamental design for a tip for syringe for taking blood samples, as shown and described.

DESCRIPTION

FIG. 1 is a perspective view of a tip for syringe for taking blood samples, showing my new design;

FIG. 2 is a side elevational view thereof, the view from the left of FIG. 2, the view from the right of FIG. 2, and the view from the side opposite that shown in FIG. 2, all being identical thereto; and,

FIG. 3 is a top plan view thereof.

The underside of the device is hidden in use and its appearance is not claimed.
